UNITED STATES PATENT OFFICE.

WILLIAM B. ERB, OF CHICAGO, ILLINOIS.

PUMP.

No. 867,261.

Specification of Letters Patent.

Patented Oct. 1, 1907.

Application filed September 2, 1905. Serial No. 276,784.

To all whom it may concern:

Be it known that I, WILLIAM B. ERB, a citizen of the United States, residing at 94 Seventy-sixth street, in the city of Chicago, county of Cook, and State of Illinois, have invented new and useful Improvements in Pumps, of which the following is a specification, reference being had to the accompanying drawings, forming a part thereof.

This invention is designed as an improvement in the construction of pumps, particularly those designed for deep wells in which there is of necessity a great length of pump rod to be lifted in the action of the pump, and in which, therefore, the reduction of the weight of such rod to the minimum consistent with strength and stiffness necessary for its work is of importance, and any means of diminishing the requirement of stiffness without incurring liability to bending or springing is of importance.

The invention consists of the features of construction set out in the claims.

In the drawings:—Figure 1 is a vertical section of pump barrel and pump rod therein embodying my invention. Fig. 2 is a section at the line 2—2 on Fig. 1. Fig. 3 is a section at the line 3—3 on Fig. 1. Fig. 4 is a section at the line 4—4 on Fig. 1.

In the drawings, 1 represents the upper portion of the barrel of the pump in which the pistons operate, the same being sunken in the well bore into water-bearing stratum, or at least so low as to be within sucking distance of the water supply. The form of this barrel as shown is that which is fully described in my Patent No. 763,664, dated June 28, 1904; and for the purpose of understanding the present invention it is not necessary to explain or describe the pump barrel or pistons therein further than to state that the construction is such as to cause double action,—that is, to lift the water by both the down stroke and the up stroke of the pump rod.

In the drawings, 2 represents the upper piston in the pump barrel. The pump rod comprises, as mentioned, sections or lengths, as may be necessary according to the depth of the well, of standard tubing, 3, 3, 3, 3, connected by standard couplings, 4, 4, 4, 4, and the well tubing above the barrel, 1, and up to within a short distance of the top, consists of as many lengths or sections as necessary of standard tubing, 5, 5, 5, joined by standard couplings, 6, 6, 6. And in practice, in a well bore which will receive, for example, a two-inch (outside diameter) pump barrel, I employ for the tube standard one and one-half inch pipe, of which the couplings are somewhat less than two inches outside diameter, and for the rod coöoperating within this tubing I employ standard three-fourths inch pipe of which the standard couplings are about one and one-fourth inch outside diameter, leaving only one-eighth of an inch all around the coupling inside the pipe.

The pipe sections, 3, constituting pump rod are perforated as indicated at 3^a to permit the water to pass in and out as the case may require. These perforations are preferably accumulated toward the opposite ends,— that is, near the couplings,—the total area of the entire group of perforations near each end being at least equal to the annular cross-section of the coupling, 6,—that is, to the obstruction which it offers to the passage of water in the tube.

Near the top of the well bore the uppermost section of pipe, 5, is connected by a reducer, 7, with a short section of pipe, 8, of larger diameter, whose length is a little more only than the stroke of the pump rod; and within this upper section, 8, the uppermost tubular section, 3, of the pump rod is coupled to a solid steel rod, 9, by means of a reducer, 10, whose upper end is of course completely closed by the rod, 9, screwed thereto, and whose cavity above the upper end of the tubular section, 3, which is screwed into the lower side of the coupling opens out to the surface of the coupling through a plurality of apertures, 10^a, thus affording communication from the interior of the tubular portion of the pump rod with the space in said larger upper section, 8, of the pump tube above the coupling. The upper solid portion, 9, of the pump rod is adapted at the upper end to be connected with any device for reciprocating the pump rod by motive power, and for that purpose it extends up through the delivery chamber, 12, of the pump and out through a stuffing box, 13, at the upper side of said chamber, a discharge pipe, 14, leading from the chamber laterally.

For the purpose of permitting the ready withdrawal of the tubing from the well when desirable for repairs to any of the parts, the delivery chamber, 12, has at the bottom an aperture, 12^a, large enough to permit the largest element of the pump tubing, which is the coupling 7, to pass freely through it; and there is secured on to the upper end of the upper large section, 8, a flange, 15, reduced in diameter for a short distance at the lower side to form a projecting nipple, 15^a, which enters the aperture, 12^a, and thereby centers the flange in the aperture, and which has on the downwardly facing surface of the shoulder which results from the reduction of diameter of said portion, 15^a, an annular groove, 15^b, which receives a packing ring which is held firmly seated upon the upper surface of the lower wall of the chamber, 12, around the aperture, 12^a, by the weight of the pump tube, which it will be perceived is supported thus directly on said lower wall of the delivery chamber at the margin of the aperture, 12^a, on which said packing thus seats. The upper wall of the delivery chamber, 12, has an aperture, 12^b, large enough to permit the flange, 15, to be withdrawn through it, and this aperture, 12^b, is closed by a cap, 16, on which is formed the stuffing box, 13, above-mentioned, through which the upper solid element, 9, of the pump

rod emerges for connection of the power. Although the weight of the pump tubing will normally usually hold the flange, 15, seated, as described, at the margin of the aperture, 12^a, it is preferably bound fast in 5 position by means of bolts, 17, 17, set through the cap, 16, and impinging upon the upper side of the flange. For withdrawing the pump tube, the cap, 16, will first be withdrawn over the end of the pump rod and the flange, 15, will be engaged by means of eyes, 15^a, 15^a, 10 which are screwed into its upper side for that purpose, and the whole pump tube may thus be drawn through the delivery chamber.

By the employment of standard gages of tubing and coupling for both the pump tubing and the pump rod, 15 the cost of construction is greatly cheapened, but this would be impracticable but for the employment of a tubular pump rod, and the flow would be greatly impeded but for the perforation of the tubular rod between the couplings as described, for it will be seen 20 that the capacity of the pump tube around the couplings, 4, is very limited, and that especially during the descending stroke the amount of water which would ascend past the couplings outside the pump rod would be very much less than could be lifted in the upward 25 movement wherein the water might be carried bodily along with the moving rod; but by making the pump rod tubular, as described, and perforating it so that the water can pass freely into and out of it around the couplings the entire bore of the tubular rod becomes 30 available for the movement of the water in both strokes, and while the dimensions of the pistons may be such that in the up-stroke none of the water carried in the tubular rod is discharged therefrom, in the down stroke the restriction of the outer passage by the approxima- 35 tion of the diameter of the couplings on the rod to the inner diameter of the pump tubing forces the water to rise through the rod in the bore thereof that in each interval between the consecutive couplings is being forced through the perforations into the inner bore 40 and is discharged through the top coupling, 10, into the upper large section, 8, of the tubing and lifted with the water which has passed up outside the pump rod into the discharge chamber.

It is not merely, however, for the purpose of reducing 45 the cost of construction that I employ the standard couplings on the tubular pump rod within standard pipe employed for the tubing, but it is especially desirable that the pump rod should at frequent intervals so closely approximate the wall of the pipe in which it 50 is placed as to prevent it from buckling or bending in the down stroke, as is liable to happen if a slender rod is employed in considerable length without frequent guide bearings. To provide guide bearings would, of course, greatly diminish the capacity of pump tubing 55 of given bore, since only through apertures in such bearings could water pass upward around the rod. But by employing the couplings on the tubular rod of a diameter so near to the inner diameter of the pipe as described—only an eighth of an inch interval all around 60 the coupling being left in the pipe—it will be seen that the tubular pump rod cannot bend or be deflected laterally except to the extent of such one-eighth of an inch in any two intervals or sections, and the utmost deflection from a straight line which can occur will be 65 that which will be involved in one coupling springing

to one side one-eighth of an inch from central position, while the next coupling, above or below, springs in the opposite direction an equal distance, and this amount of deflection will not cause the tubular pump rod to be bent or materially interfere with its perfect action. 70 There is an additional advantage which is obtained by the approximate feature of the couplings on the pump rod to the inner diameter of the pump tubing. Continuous use of any pump drawing water which carries a considerable amount of mineral, either in solution or 75 in suspension, causes the formation of scale on the inside of the pipe, which not only reduces its operative diameter but also is liable to injure the valves by becoming loosened and falling into the tube on to the valves in the pump barrel below. When the entire 80 water capacity of the pump tube is obtained outside the pump rod, and when for that reason it is necessary to construct the pump rod so that it does not at any point very closely approximate the inner wall of the pump tube, scale of this sort may form in considerable 85 thickness before it will become detached, and the same circumstance which permits it to form so thick—the comparatively wide interval necessary to be maintained between the pump-rod couplings and the tube wall—permits such large fragments of scale to fall to 90 the pump barrel with the resulting damage above indicated. In the construction herein described, however, the couplings, 4, on the tubular pump rod work at all times so close to the inner wall of the tube, sometimes touching at one point and sometimes at another 95 in the circumference of the tubing as the rod chances to spring one way or the other in the down stroke. These couplings keep the inner wall of the tube wiped clean of the material which would form the scale so that it is kept constantly either in suspension in the water 100 and is carried up and discharged with it, or if occasionally a piece of scale too heavy to be thus carried does have opportunity to be formed on the pipe before it is wiped off by the coupling, it is almost certain to be chafed and ground between the pipe and two or more 105 couplings on the rod before it reaches the bottom and either is reduced to fragments too small to be injurious or so small as to be caught and lifted by the ascending current before it reaches the bottom. In practice, therefore, I find that the construction above described 110 results in a clean tube and greatly increased life of the valves in the pump barrel at the bottom.

I claim:—

1. In a well pump, in combination with the well tubing and the pump cylinder at the lower end thereof, a tubular pump rod extending from the cylinder up within the well tubing, composed of lengths or sections of pipe and exterior couplings uniting them, the several pipe sections of the tubular rod being apertured between the couplings for the passage of water between the longitudinal cavity 115 of the rod and the space outside the same in the well tubing.

2. In a well pump, in combination with the well tubing and the pump cylinder at the lower end thereof, a tubular pump rod extending from the cylinder up within the well tubing, composed of lengths or sections of pipe and exterior couplings uniting them, the several pipe sections of the tubular rod being apertured between the couplings for the passage of water between the longitudinal cavity 120 of the rod and the space outside the same in the well tubing, the total area of the apertures in each of said lengths or sections of pipe being as great as the annular cross section of the coupling or structure which it presents 125 to the passage of water through the well tubing.

3. In a well pump, in combination with the well tubing and the pump cylinder at the lower end thereof, a tubular pump rod connected with the cylinder consisting of lengths or sections of pipe and exterior couplings uniting them, the exterior diameter of the couplings being only slightly less than the interior diameter of the tubing, the several sections or lengths of pipe constituting the rod being apertured between the couplings for the passage of water into the rod to compensate for the obstruction which the 10 couplings offer to the passage of water through the tubing

outside the rod, and means at the upper end of the rod for delivery of the water therefrom.

In testimony whereof, I have hereunto set my hand, in the presence of two witnesses, at Chicago, Illinois, this 28th day of August, 1905.
